UNITED STATES PATENT OFFICE.

CARL ALEXANDER ERBSLÖH, OF BARMEN, GERMANY.

FRICITION DRIVING MECHANISM FOR ROLLING-MILLS.

SPECIFICATION forming part of Letters Patent No. 722,685, dated March 17, 1903.

Application filed October 25, 1901. Serial No. 80,026. (No model.)

To all whom it may concern:

Be it known that I, CARL ALEXANDER ERBSLÖH, rolling-mill owner, a subject of the King of Prussia, German Emperor, residing at No. 5 2 Schönenstrasse, Barmen, in the Kingdom of Prussia, Empire of Germany, have invented certain new and useful Improvements in Friction Driving Mechanism for Rolling-Mills; and I do hereby declare the following to be a 10 full, clear, and exact description of the invention, such as will enable others skilled in the art to which it appertains to make and use the same.

My present invention relates to a driving mechanism for the upper roll of rolling-mills, in which motion is directly imparted to the upper roll by means of cog-wheels seated upon the gudgeons of the rolls without any intermediate parts.

20 In cases where the upper roll of heavy rolling-mills received its motion by means of cog-wheels it was hitherto customary to arrange the latter at a considerable distance from the rolls themselves and transmit the power from 25 the wheel for the upper roll to the latter with the aid of an interposed bar coupled to the wheel-shaft and to the roll after the manner of universal joints; but this driving mechanism for the upper roll demands very much 30 space, the wheel for the upper roll must be provided with extra bearings, and the pliable connection of said intermediate bar with the cog-wheel, on the one hand, and with the upper roll, on the other hand, are very disadvantageously strained, and hence wear out very 35 rapidly, so that frequent repairs and inaction of the mill are unavoidable, causing loss of time and money.

The object of the present invention is to 40 avoid all these drawbacks and to provide a driving mechanism for the upper roll of heavy rolling-mills which enables me to save a great amount of valuable space and at the same time to simplify the construction of the mechanism and prolong its life, as the extra bearings for the wheel and the intermediate bar connecting it with the upper roll are not any more needed. The cog-wheels are now directly placed upon the ends of the gudgeons 45 of the rolls, so that the motion of the under roll is transferred to the gudgeon of the up-

per roll without any other parts than said wheels.

In the accompanying drawings, Figure 1 is a side view of the driving mechanism, partly 55 in section; and Fig. 2 is a vertical section on line A B of Fig. 1.

The coupling *a* of the driving-shaft *b* is placed over the indented part *c* (of clover-leaf section) of the gudgeon *d* of the lower roll *e*. 60 Between the coupling *a* and the gudgeon *d* proper is securely keyed the recessed cog-wheel *f*. Upon the reduced cylindrical part *g* of the gudgeon *h* of the upper roll *i* is movably mounted the cog-wheel *k*, meshing with 65 the cog-wheel *f* of the lower roll *e*. The wheel *k* is recessed on both sides, into which recesses the wooden rings *l* and *m* are partly sunk. (See Fig. 1.) After said wooden rings and the wheel *k* are put in place a heavy washer 70 *n* is pressed against the outer wooden ring *l* by screw *o*, thus uniting the wheel *k* with the upper roll *i* and rotating the latter by means of the created friction, as the connection of the rolls by means of cog-wheels can under 75 no conditions whatever be a rigid one, because the diameters of the rolls are never exactly equal, for which reason the upper roll would gain a lead over the under roll, or vice versa, thus surely leading to the destruction 80 of the cog-wheels if both were rigidly connected with the rolls. The pins *p* and *q* prevent the washer *n* from rotating.

The gudgeons *d* and *h* are journaled in the post *r* of the mill-frame and may be accomplished in any known manner, which details are not shown here, as such and other parts of the machine are not forming a part of this invention.

I claim—

1. A friction driving mechanism comprising a driving cog-wheel, an object to be driven provided with a cylindrical part and a shoulder, a second cog-wheel loosely seated upon said cylindrical part of the object to be driven 95 and meshing with the first-named cog-wheel, a divided friction-ring seated between the inner side of said second cog-wheel and the shoulder formed on said cylindrical part, a washer larger in diameter than said cylindrical part and having pins entering the end of said cylindrical part to prevent the rotation of said 100

washer, a second divided friction-ring seated between the outer side of said second cog-wheel and said washer, and a tightening-screw to attain degrees of friction necessary between the 5 second cog-wheel and the object to be driven to overcome various degrees of resistance.

2. In a friction driving mechanism of the kind described the combination of a driving cog-wheel, an object to be driven provided 10 with a cylindrical part and a shoulder, a second cog-wheel meshing with the first-named cog-wheel and seated upon said cylindrical part of the object to be driven, a divided friction-ring seated between said second cog- 15 wheel and the shoulder formed on said cylindrical part, a washer larger in diameter than

said cylindrical part and having pins entering the end of said cylindrical part, a second divided friction-ring seated between the outer side of said second cog-wheel and said washer, 20 and a tightening-screw to attain degrees of friction necessary between the second cog-wheel and the object to be driven to overcome various degrees of resistance.

In testimony that I claim the foregoing as 25 my invention I have signed my name in presence of two subscribing witnesses.

CARL ALEXANDER ERBSLÖH.
